SOUND SIGNALS

Joe White, Anderson, Ind., assignor to General Motors Corporation, Detroit, Mich., a corporation of Delaware

Application October 27, 1952, Serial No. 317,066

4 Claims. (Cl. 340—388)

This invention relates to sound signals, particularly those used under damp or moist conditions, and/or which are to be protected against radio interference.

A mounting plate is provided with a peripheral flange or ledge adapted to be engaged by an impervious cover with interposed sealing means, so as to prevent the passage of moisture and a lead-in assembly for the magnet motor is supported by the cover through the agency of a weatherseal, the lead-in assembly, cover and base plate being metallically connected to provide shielding against radio interference. All junctures between the cover, base and motor structure, are sealed by compressible rings or bands and grommets. A structure of this kind is particularly desirable in army tank constructions which are subject to operation under adverse circumstances.

Further objects and advantages of the present invention will be apparent from the following description, reference being had to the accompanying drawings wherein a preferred embodiment of the present invention is clearly shown.

In the drawing:

Fig. 1 is a top plan view, with a section through the cover, all illustrating the features of the instant invention.

Fig. 2 is a vertical section substantially as indicated by the line and arrows 2—2 of Fig. 1.

Fig. 3 is a longitudinal section of the terminal assembly substantially as indicated by the line and arrows 3—3 of Fig. 1.

With reference to the drawing, 10 identifies a base plate or mounting plate having apertured lugs 12 by which the device may be mounted on any convenient structure. Surrounding the base plate there is a vertical wall 14 terminating in an off-set flange 16 about the periphery of the plate. Mounting lugs 12 are extensions from the flange 16. On top of the base plate as seen in Fig. 2, a magnet motor 18 is mounted, that comprehends a U-shaped field frame 20 centrally apertured to receive an extension 22 of a cylindrical field core 24 that also passes through the base plate 10, a spacing washer 26, a resonator plate 28 and a clamp washer 30 against which the end of the core member is peened over as at 32. A compressible seal ring 34 is disposed in a concavity of the spacer 26 so as to be compressed into sealing relation when the parts are secured together by the peening at 32.

The field frame 20 provides a pair of parallel legs or arms 36 and 38 diametrically disposed on opposite sides of a field winding or coil 40 carried by the core member 24 that ends in a pole piece 42. Attached to the leg 36 there is a bracket 44 that supports a resistor element 46 and a circuit breaker assembly 48, and provides a bendable back stop 50. The leg 38 of the field frame is somewhat longer than the leg 36 and provides a notch between parallel portions 52, within which notch there is disposed a neck portion 54 of an armature hinge plate 56. The neck portion of this plate is formed by notches 58 extending inwardly toward each other from the oppo-

2

site edges of said plate 56, more particularly as shown in Fig. 1. On the hinge plate 56 there is secured a magnetic plate 60 secured thereto by rivets 62 and 64, the latter being of brass and being disposed at the mathematical center of percussion for striking the pole piece 42 when the magnet motor is energized.

A spring 66 hooked to bracket 68 mounted on the leg 38 of the field frame, and over a tongue 70 of the armature plate, rocks the armature assembly over the end of the leg 38, so that the end of the armature will rest against the underside of the back stop 50. The circuit breaker assembly 48 embodies a flexible leaf 72 carrying a movable contact 74 normally engaging a fixed contact 76 on the plate 77 when the field winding 40 is not energized. To a terminal board 80 a lead-in wire 82 is anchored at 84, where electrical connection is made with a wire 86 anchored in an opening 88, and thence connecting by 90 to the winding 40. From the coil or winding connection 92 returns to the terminal board with anchorage at 94, from which connection is made by wire 96 to an anchorage lug 98 on the plate 77, and thence to one side of the resistance element 46 by connection 100.

The opposite end of the lead-in wire 82 is connected at 102 to the core member 104 of a capacitor assembly 106 secured to a bushing 108 for mounting in the wall of a cover 110. The core member 104 engages a connector plate 112 connecting with one electrode or foil 114 of a dry condenser, a second foil 116 in insulated relation to the foil 114 connecting with a condenser casing 118. The casing 118 is necked down at 120 to telescope inside of the bushing 108 where it is bonded or otherwise detailed to make electrical connection with the bushing. The usual insulators and sealing washers or discs 122 and 124 perfect the usual sealing of the capacitor, and insulation of the respective conductors and electrodes all as is well known to those experienced in the art.

The core member 104 extends axially of the bushing 108 to provide a connector tip 126 centrally disposed of a connector sleeve 128 having bayonet provisions for connecting the usual wiring harness. About the terminal tip 126 and within the sleeve 128 there are provided insulators and sealing washers 130 to prevent the entrance of moisture. This capacitor assembly is mounted in the side wall of the cover 110 as shown in Fig. 1 where it is fitted with a clamp nut 132 cooperating with the threaded portion 134 for compressing a grommet or sealing washer 136 to prevent the passage of moisture. Electrical conductivity for shielding is perfected by placing the grommet 136 on the inside of the cover, and the clamp nut 132 on the outside where it may engage the cover 110 when tightened on the threaded portion 134.

The cover 110 has a flange 138 around the perimeter that is coextensive with the offset flange 16 of the base plate 10. When the cover 110 is placed over the magnet motor 18 and telescoped with the vertical wall 14, the flange 138 engages a compressible sealing strip 140 supported by the flange 16 on the base plate. Tangs or interrupted flange portions 142 extending from the cover are then bent over and forced against the bottom side of the flanges 16, which compresses the sealing strip and perfects a shielding connection between the cover 110 and base 10.

While the embodiment of the present invention as herein disclosed, constitutes a preferred form, it is to be understood that other forms might be adopted.

What is claimed is as follows:

1. In a sound signal a magnet motor comprising, a U-shaped field frame, a field coil and core secured to the center portion of said frame, a circuit breaker assembly carried by one leg of the frame, a vibratable armature

hingedly connected to the other leg of the frame and extending into engageable relation with said circuit breaker for actuating said circuit breaker when said magnet motor is energized, a back stop for the armature, spring means normally urging the armature against the back stop, and a nonmagnetic brass rivet carried by the armature and adapted to engage the core of said field coil when the magnet motor is energized.

2. The combination set forth in claim 1 wherein the field core extends through the frame and a base plate and is secured to a resonator plate to be sounded by the operation of said magnet motor.

3. In a sound signal device, a magnet motor comprising, a field frame of U-shape having parallel arms of unequal length, a circuit breaker assembly carried by the shorter arm, and an armature assembly having interlocking engagement with the longer arm, a back stop extending from said circuit breaker normally engaged by said armature, a field winding including a core member disposed between the arms of said field frame, a mounting 20 adapted to be secured to said support and field frame and having an apertured plate through which a portion of the core member extends, and a resonator plate having an aperture therein and secured in spaced relation on the side of the mounting plate remote from said frame 25

by a portion of the core which extends through the aperture in said resonator plate.

4. In a vibration motor, a magnet coil having a central core, a U-shaped field frame secured to and embracing the magnet core and having one arm ending in a notched end portion, an armature assembly having a hinge plate interlocking with the notched portion of said arm to provide a hinging action, a circuit breaker assembly carried by the other arm providing a back stop engageable by said armature assembly, and a flexibly supported contact movable by said armature assembly when actuated by said magnet coil.
